UNITED STATES PATENT OFFICE

149,247

DESIGN FOR A HOUSING FOR A MOTION-PICTURE PROJECTOR OR SIMILAR ARTICLE

Ewald Boecking, Great Kills, Staten Island, N. Y., assignor to Manufacturers Machine & Tool Co., Inc., Mount Vernon, N. Y., a corporation of New York

Application July 30, 1947, Serial No. 140,607

Term of patent 14 years

(CL. D61—1)

To all whom it may concern:

Be it known that I, Ewald Boecking, a citizen of the United States of America, residing at Great Kills, in the county of Richmond, State of New York, have invented a new, original, and ornamental Design for Housing for a Motion-Picture Projector or Similar Article, of which the following is a specification, reference being had to the accompanying drawing, forming part thereof.

Fig. 1 is a side elevational view of a motion picture projector showing my new design.

Figure 2 is a perspective view of the opposite side and of the front and top of the housing illustrated in Fig. 1;

Figure 3 is an elevation of the rear of the housing shown in the other figures; and

Figure 4 is an elevation of the front of the housing.

The stippling is for shading only.

The essential features of my design are shown in solid lines.

I claim:

The ornamental design for a housing for a motion-picture projector or similar article, as shown and described.

EWALD BOECKING.
